UNITED STATES PATENT OFFICE.

MICHAEL J. FOLEY AND GUY L. ROGERS, OF CLOQUET, MINNESOTA.

END BEARING FOR ROLLS.

SPECIFICATION forming part of Letters Patent No. 664,251, dated December 18, 1900.

Application filed April 5, 1900. Serial No. 11,784. (No model.)

To all whom it may concern:

Be it known that we, MICHAEL J. FOLEY and GUY L. ROGERS, citizens of the United States, residing at Cloquet, in the county of Carlton and State of Minnesota, have invented certain new and useful Improvements in End Bearings for Calender-Rolls, of which the following is a full, clear, and exact specification, reference being had therein to the accompanying drawings, in which—

Figure 1 is an end elevation of a portion of a calendering-stack, showing several rolls provided with our improved end bearing; Fig. 2, a horizontal section through the side frames, showing one of the devices in plan; and Fig. 3, a vertical section showing the adjustable end bearing-block.

This invention has reference to that class of calendering-machines in which a vertical series of rolls resting one upon the other are employed, the ends of the roll-shafts being journaled in boxes vertically slidable in the frame-standards. In high-speed calendering-machines of this sort the rolls have a tendency to crowd endwise against the journal-boxes, which causes undue friction and heating at the ends of the rolls, which results in a considerable loss of power expended in driving the rolls and also in a loss of paper and time.

It is the object of our invention to avoid this difficulty; and the invention consists, essentially, in mounting upon one or more of the journal-boxes a supporting-yoke carrying an adjustable end bearing arranged in axial alinement with the shaft of the roll, so as to bear endwise directly on the end of the roll, whereby the end thrust of the roll may be nicely adjusted and equalized, as more fully hereinafter set forth.

Referring to the drawings by reference-letters, *a* designates the calender-rolls; *b*, the journal-boxes, through which the ends of the shafts of the calender-rolls pass, and *c* the frame-standards, in which the boxes *b* vertically slide in the usual manner. Bolted to the outer face of each journal-box is a yoke or arch *d*, which extends horizontally across the center of the journal-box, its central part lying near to and slightly beyond the end of the shaft of the roll. Carried by this yoke and bearing upon the end of the shaft is a

bearing-block *e*, preferably of lignum-vitea, which is adjustably supported on the yoke by means of a screw-bolt *f*, which is tapped 55 through the yoke and is connected by a swivel to the outer face of the plate *g*, rigidly fastened to the bearing-block *e*, said plate *g* being provided with outward-extending flanges *h*, which respectively engage the upper and lower edges of the yoke and guide the bearing-block in its inward and outward movements and prevent its rotating, the screw-bolt being provided with a lock-nut *i* to lock the parts in their adjusted position. 65

It will be observed that by adjusting and locking the end bearing-block *e*, which bears directly upon the axial center of the roll-shaft, the endwise pressure of the roll against the bearing-ring on the inner side of the journal-box may be nicely regulated. In this way the end thrust of the roll may be properly distributed between the main bearing at the inner side of the journal-box and the auxiliary bearing at the extreme outer end of the 75 shaft, it being preferable to so adjust the devices that most of the thrust shall be taken up by the auxiliary bearing, whereby undue friction between the end of the roll and the journal-box and the consequent overheating 80 of the parts are avoided and considerable saving in time and paper is effected. It will be observed that it is essential that the auxiliary end bearing be supported entirely on the journal-box, so that it will move bodily 85 vertically with the same as the calender-rolls are adjusted.

As the journal-boxes of calendering-machines are usually cooled by circulating water through them, it is obvious that any thrust-bearing which forms a part of the box cannot be employed upon such bearings, because the journal-box must be closed permanently and be water-tight. It will be observed that our invention avoids this objection, as it is wholly 90 outside of the journal-box, permitting the journal of the roll to extend entirely through and beyond the outer side of its box. It is further essential that the end bearing or step must be independent of the journal-box and 100 be detachable therefrom, so that it may be attached to any stack of rolls and be changed from one roll to another as the exigencies of the case may require. We have found that

it is not necessary to have one of the steps on each box, as there are times when all the rolls do not crowd, so that by having several of the yokes or steps they can be changed from 5 one roll to the other at will and without stopping the machine or losing or destroying paper. It is also essential that the yoke be so constructed that it may be applied to journals of varying length, which would be practically impossible if the part carrying the end bearing-block were a part of the journal-box proper.

Having thus fully described our invention, what we claim, and desire to secure by Letters 10 Patent, is—

In combination, a frame, a journal-box supported thereon, a roll journaled in said box the end of its journal projecting through and beyond said box, a yoke secured to the outer 15 side of said box and extending across the

axial line of the roll, a wooden antifriction bearing-block bearing on the extreme end of the roll-journal, a supporting-plate secured to the rear side of the bearing-block, outward-extending arms on said plate and slidably engaging the yoke to prevent the rotation of the block, an adjusting-screw carried by the yoke axially in line with the roll and connected by a swivel to the supporting-plate, and means for locking said screw, substantially as described and for the purpose set forth. 25 30

In testimony whereof we hereunto affix our signatures, in the presence of two witnesses, this 21st day of March, 1900.

MICHAEL J. FOLEY.
GUY L. ROGERS.
